(57) **CLAIM**

The ornamental design for a manned aerial vehicle, as
shown and described.

DESCRIPTION

The patent or application file contains at least one drawing
executed in color. Copies of this patent or patent application
publication with color drawing(s) will be provided by the
Office upon request and payment of the necessary fee.

FIG. 1 is a top-right perspective view of a manned aerial
vehicle;

FIG. 2 is a top-right perspective view thereof;

FIG. 3 is a top-right-front perspective view thereof;

FIG. 4 is a front-right perspective view thereof;

FIG. 5 is a front-left perspective view thereof;

FIG. 6 is a top-left-front perspective view thereof;

FIG. 7 is a top-left perspective view thereof;

FIG. 8 is a top-right-rear perspective view thereof;

FIG. 9 is a left-rear perspective view thereof;

FIG. 10 is a right-rear perspective view thereof;

FIG. 11 is a bottom-right-rear perspective view thereof;

FIG. 12 is a bottom-right-rear perspective view thereof;

FIG. 13 is a bottom-right-front perspective view thereof;

FIG. 14 is a bottom-right-front perspective view thereof;

FIG. 15 is a bottom-left front perspective view thereof;

FIG. 16 is a bottom-left-front perspective view thereof;

FIG. 17 is a bottom-left-rear perspective view thereof;

FIG. 18 is a bottom-left-rear perspective view thereof;

FIG. 19 is a front elevation view thereof;

FIG. 20 is a right elevation view thereof;

FIG. 21 is a left elevation view thereof;

FIG. 22 is a rear elevation view thereof;

FIG. 23 is a top plan view thereof;

FIG. 24 is a bottom plan view thereof;

FIG. 25 is a top-right perspective view thereof, with a
canopy thereof in an open position;

FIG. 26 is a top-front-right perspective view thereof, with the
canopy in the open position;

FIG. 27 is a top-right-rear perspective view thereof, with the
canopy in the open position;

FIG. 28 is a left elevation view thereof, with the canopy in
the open position;

(Continued)

FIG. 29 is a right elevation view thereof, with the canopy in the open position;
FIG. 30 is a left-rear perspective view thereof, with a rear hatch thereof in an open position and including a litter;
FIG. 31 is a top-right-rear perspective view thereof, with the rear hatch in the open position and including the litter;
FIG. 32 is a top-right-front perspective view thereof, with the rear hatch in the open position and including the litter;
FIG. 33 is a bottom-left-rear perspective view thereof, with the rear hatch in the open position and including the litter;
and,
FIG. 34 is a left elevation view thereof, with the rear hatch in the open position and including the litter.
